DISTILLATION OF OIL

David G. Brandt, Westfield, N. J., assignor, by
mesne assignments, to Power Patents Com-
pany, Jersey City, N. J., a corporation of Maine

Application January 31, 1922, Serial No. 532,953
Renewed January 14, 1928

32 Claims. (Cl. 196—66)

This invention relates to the distillation of oil, and more particularly to a process of and apparatus for cracking high boiling point oil distillates to obtain low boiling point distillates such as gasoline.

The major portion of all gasoline which is made today by cracking high boiling point distillates is made by treating the oil in large cylindrical batch stills. The cracking of the oil in these intermittently operated stills has been confined to the treatment of the high boiling point distillates, such as fuel oils, because the limitations of the mechanical construction, and the necessity of safe operating conditions will not permit these large stills to be operated at the high temperatures and pressures required for cracking the lower boiling point distillates such as kerosenes. When the high boiling point distillates are cracked a large amount of carbon is deposited, and if a still containing free carbon is directly heated, coke deposits are formed which require that the still must be stripped at frequent intervals to be cleaned.

An object of the present invention is to provide a process of and apparatus by which high boiling point distillates may be effectively cracked in a continuous operation.

Another object of the invention is to provide a process of and apparatus by which high boiling point distillates may be effectively cracked without being subjected to the direct contact of the furnace combustion gases.

In the preferred embodiment of the invention a high boiling point distillate is maintained in an elongated column and heated to a cracking temperature by vapors of a lower boiling point distillate, such as kerosene. The kerosene is vaporized under pressures of 125 to 200 pounds per square inch, in order to obtain vapors at a temperature of 800° to 825° F., so that vapors at this temperature may be used for cracking the high boiling point distillate. When using low boiling point vapors for cracking high boiling point oil it is necessary that the temperature of this oil should be held above the condensing point of the vapors to prevent the gravity and boiling point of the oil from being lowered to substantially the gravity and boiling point of oil from which the vapors are formed. This may be accomplished by supplying a sufficient quantity of vapors or by superheating a part or all of the vapors.

Accordingly, another object of the invention is to provide a process of cracking high boiling point distillates by heating them under pressure to a

cracking temperature with a vapor of a lower boiling point distillate.

The use of a vapor heating medium in the present invention permits a high boiling point distillate to be cracked without applying heat directly to the still in which it is cracked.

With this in view, another object of the invention is to provide a process of and apparatus by which a high boiling point oil may be cracked by heating it to the cracking temperature with 10 vapors of an oil which can be vaporized under pressure without depositing substantial amounts of carbon in the heater.

With these and other objects and features in view, the invention consists in the process of and apparatus for cracking oil hereinafter described and particularly defined in the claims.

In the accompanying drawing is diagrammatically illustrated an apparatus in which the preferred form of the invention may be carried out.

To carry out the process outlined above in the apparatus shown in the drawing, a high boiling point hydrocarbon oil, such as fuel oil, is supplied through a pipe 10 to a pump 12 and forced through a pipe 14 into a series of fractional condensers 16. The high boiling point oil is pre-heated in the fractional condensers 16, and passes from the condensers through a pipe 18 into the upper end of a cracking still 20. The oil introduced into the upper end of the still overflows from a series of trays 22 where it acts to scrub vapors rising from the main body of oil within the cracking chamber. The volume of oil introduced upon the trays 22 is preferably controlled to hold back the high boiling point fractions of the vapors, so that they may be returned to the body of the oil in the still to again be cracked.

To carry on the cracking operation within the still 20, a lower boiling point hydrocarbon oil, such as kerosene, is supplied through a pipe 24 to a pump 26 and forced through a pipe 28 into the upper portion of a dephlegmating section 30 of a tower 32. The kerosene or low boiling point hydrocarbon overflows over a series of hoods 34 where it acts to scrub vapors leaving the cracking chamber 20 and introduced into the dephlegmator through a pipe 36. By this scrubbing action hydrocarbon vapors of a lower boiling point than those condensed in the upper end of the still 20 are held back and preferably these vapors have substantially the boiling point of the kerosene introduced by the pump 26. The kerosene and condensate which reaches the bottom 38 of the dephlegmating section 30 pass out through a 55

pipe 40 to a pump 42, by which they are forced through a pipe coil 44 positioned within a furnace 46. The oil enters the pipe coil 44 at the bottom or the coolest portion of the heating chamber and its temperature is gradually increased as it flows through the coil. The oil and vapor leaving the coil pass through a pipe 48 and are discharged into the upper portion of a separator 50 formed within the tower 32. The vapors separated from the oil rise to the top of the separating chamber 50 and pass out through a pipe 51 by which they are introduced into the lower portion of the cracking still 20. The vapors introduced into the bottom of the cracking still pass in a circuitous path around a series of distributing baffles 54, which causes the oil and vapors to have a long path of contact to assist in heating the high boiling point oil and to aid in cracking the high boiling point oil.

When the kerosene passes through the coil 44 practically all of it is vaporized, and if this vapor is depended upon to maintain the oil in the cracking still 20 at its cracking temperature it is necessary to circulate a very large volume of vapors through the body of oil to maintain its temperature sufficiently high to prevent the vapors from being condensed therein. If the vapors are condensed, the gravity and boiling point of the oil will be lowered to substantially the same as the gravity and boiling point of the kerosene, so that the cracking operation will be seriously interfered with. To avoid the use of an excess volume of kerosene vapors a portion or all of the vapors may be removed from the chamber 50 through a pipe 52, and passed through a superheating coil 53, positioned above tile in the roof of the furnace 46. From the coil 53 the superheated vapors pass through a pipe 55 which connects with the pipe 51. A valve 56 positioned in the pipe 51 may be used to control the amount of vapor passing through the superheating coil and the pipe 51. A valve 57 positioned in the pipe 52 may be used to cut off the circulation of vapors through the pipe 52 and coil 53. The coil 53 is of comparatively small size and vapors can be circulated through the coil at such a high rate that substantially no carbon will be deposited therein. If carbon trouble is encountered in the coil 53, steam may be introduced into the coil through an injector 58 which will effectively prevent the formation of carbon in the coil. It is preferred, however, to avoid the use of steam if possible.

The oil which is separated from the vapors in the separator 50 flows downwardly through a pressure seal tube 59 and collects in a reservoir 60 formed between the outer surface of the tube and the inner surface of the tower 32. The tube 59 extends downwardly in the tower 32 a considerable distance vertically below the connection of the pipe 51 with the cracking chamber 20 whereby a sufficient liquid head will be maintained in the separator to force the gas from the separator into the bottom of the cracking chamber. The oil which accumulates in the reservoir 60 flows through an outlet 61 to the pipe 40 to be circulated, along with the low boiling point oil coming from the dephlegmating chamber 30, through the heating coil 44.

As outlined above, the vapors set free in the cracking chamber 20 are first scrubbed by the high boiling point oil advancing to the cracking chamber and are next scrubbed by the kerosene or lower boiling point oil which is passing to the pipe still 44. By these two scrubbing operations

a large portion of the high boiling point fractions is removed from the vapors. The remaining portion of the high boiling point fractions is removed by means of a steam boiler condenser 62, forming the upper end of the tower 32. Some of the vapors in a condenser 62 are condensed by means of water or steam which are positioned within a chamber 64 surrounding a series of tubes 66 which pass through tube sheets 68 and 70 positioned at opposite ends of the chamber 64. Water is continuously introduced into the chamber 64 through an inlet 72, and steam is continuously removed from the chamber by means of an outlet 74. To vary the boiling point of the vapors leaving the condenser 62 a series of tubes 76 are telescopically mounted within the tubes 66 and may be adjusted vertically by means of a screw 78 operated by a motor 80. By vertically adjusting the tubes 76 the area of the tubes 66 in contact with the vapors may be varied to vary the condensing effect on the vapors.

The vapors leaving the condenser 62 pass through a pipe 82 to the first of the fractional condensers 16. In the condensers 16 the vapors are fractionally condensed by a heat interchange with the high boiling point oil advancing to the cracking still 20, and any desired number of fractions may be recovered. When treating heavy distillates such as fuel oil and gas oil it is desirable that the fractional condensers shall separate from the vapors all constituents except the vapors which should be condensed as a gasoline cut. Accordingly, the vapors leaving the last condenser 16 pass through a pipe 84 which is provided with a pressure reducing valve 86, by which the pressures of the vapors may be reduced to substantially atmospheric pressure to be cooled and condensed in the water cooled condenser 88. Any uncondensed vapors reaching a separator 90 from the condenser 88 pass outwardly through a pipe 92 and the condensate is removed through a pipe 94. If it is desired to use several of the fractional condensers 16 for condensing the gasoline fractions, a pressure reducing valve may be placed in any of the vapor lines 95 connecting the adjacent condensers. The condensate recovered in the condenser 16 passes downwardly into traps 96 and may be collected in a header 98 and returned through a pipe 100 to the pump 26, to be again circulated through the dephlegmator and pipe still. In case some of the condensers 16 are used for condensing a gasoline fraction, or any desired distillate, suitable valves and piping connections with the traps 96 are provided, whereby the desired fractions may be separately collected.

The high boiling point distillates such as fuel oil and gas oil are more unstable than the lower boiling point distillates, such as kerosene, and the higher boiling point fractions can be cracked or decomposed at much lower temperatures and pressures than the lower boiling point distillates. The high boiling point distillates, moreover, deposit carbon quite rapidly when subjected to high temperatures. This deposition of carbon greatly hinders the cracking operation and has practically limited, heretofore, the cracking of oil to an intermittent operation to permit the still to be stripped periodically, to be cleaned. In accordance with the example given above of the present invention, the fuel oil is heated to a cracking temperature within the still 20 by vapors of the kerosene which are heated in the pipe still to a temperature sufficiently high to crack fuel oil. Pressures of approximately 125 to 200 pounds per square inch, depending upon the character

and quality of the oil, are maintained within the pipe still, and at those pressures the kerosene will vaporize at temperatures sufficiently high to crack gas oil and fuel oil without depositing carbon 5 within the pipes of the pipe still 44. Both the sensible heat and heat of vaporization of the kerosene vapors are available for maintaining a cracking temperature of the high boiling point oil and by superheating the vapors the temperature 10 of the oil may be accurately controlled.

When fuel oil is cracked, any carbon which is deposited in the still will float in the oil and gradually work its way to the bottom of the still and will not be formed into a hard coke because 15 the still 20 is not subjected to direct heat of combustion gases. The agitation of oil in the still 20 by the vapors circulated therethrough will assist in carrying the carbon around the baffles 54, and permit it to pass into a collecting chamber 20: 104.

The carbon and the heavy oil residuum which collect in the chamber 104 may be intermittently withdrawn to prevent the oil in the cracking chamber from becoming so heavy as to interfere 25 with the proper cracking operation. To accomplish this, a sludge pot or still 106 is connected by means of a pipe 108 with the lower portion of the still 20. A valve 110 is positioned in the line 108 and is normally closed during the operation 30 of the cracking still. When a sufficient volume of the residuum has accumulated in the chamber 104, the valve 110 is opened to allow the pressure within the cracking still 20 to blow the residuum out of the chamber 104. While the residuum is 35 being forced into the still 106, a valve 112 in a residue draw-off is closed and a valve 114 in a vapor line 116 is closed. After the residuum has been removed from the chamber 104 the valve 110 is closed and the vapor line valve 114 is 40 opened to reduce the pressure in the still to substantially atmospheric pressure. In the still 106 the superheat of the oil residuum derived from previously heating the oil under high pressure will cause an evaporation of the lighter fractions 45 of the oil residuum, and these vapors are condensed in a condenser 118. Preferably the condensate recovered in the condenser 118 is returned through a line 120 to the fuel oil pump 12 to be again returned to the cracking still 20. After the residuum has been evaporated in the still 106 it is withdrawn through the outlet valve 112 and may be passed, if desired, through a heat 50 interchanger for preheating kerosene which is advancing to the pump 26.

In the normal operation of the process a very small amount of kerosene will be introduced into the apparatus through the pipe 24, due to the fact that a large amount of the kerosene or lower boiling point distillate is formed in cracking the heavy oil in the still 20, and these fractions are removed from the vapors leaving the still in the dephlegmator 30, the condenser 62 and the condensers 16, and returned to the kerosene circuit in the dephlegmator 30. The continued circulation 55 of the kerosene from the separator through the pipe still and back tends to deposit some carbon in the oil and the constant evaporation of the oil will gradually increase its gravity. The carbon and the heavy residuum which are formed in the separator settle to the bottom of the tower 32 and may be withdrawn through an outlet pipe 122 to the still 106. At the time the residuum is withdrawn from the separator chamber 60 the valve 110 in the cracking still outlet is closed, the valves 70 112 and 114 of the still 106 are closed, and a valve

124 in the line 122 is opened to allow the pressure in the separator to force the residuum into the still 106. When sufficient oil has been removed from chamber 60 the valve 124 is closed and the valve 114 opened to permit the residuum to vaporize under reduced pressure. The condensate from the residuum may pass from the condenser 118 through the line 120 to be returned by the pump 12, to the cracking still 20.

When the specific gravity of the oil in the chamber 60 increases substantially above the normal specific gravity of the kerosene being vaporized, the oil from the chamber may be periodically transferred from the chamber 60 to the cracking still 20. To accomplish this a pipe connection 126 between the line 40 and the cracking still 20 is provided with a valve 128 by which oil may be introduced from the chamber 60 into the top of the cracking chamber. To transfer the oil from the chamber 60 to the cracking chamber a valve 130 in the kerosene line 40 is closed, a valve 132 in the kerosene vapor line is closed, and valve 128 is opened. Thereupon the vapor pressure in the separator 50 will force oil from the chamber 60 through the outlet 61, line 40 and line 126 into the cracking chamber. When sufficient oil has been removed from the chamber 60 so that the addition of kerosene thereto will lower its specific gravity to the desired point, the valve 128 is closed and the valves 130 and 132 are opened to continue the normal operation.

To secure the most efficient operation in the cracking chamber, it is necessary that the volume and temperature of the kerosene or low boiling point oil vapor which is introduced into the cracking chamber shall be sufficient to maintain the temperature of the oil in the cracking chamber at such a point that substantially no oil vapors of the specific gravity or boiling point of the kerosene will be condensed in the oil bodies. If the kerosene vapors are superheated the amount of vapors required for heating the oil body may be decreased. Therefore, by controlling the amount of vapors being superheated the amount of raw kerosene being introduced and temperature in the condensers may be controlled.

Although the invention has been described as a process for cracking fuel oil by heating the oil with kerosene vapors, the invention is not limited to the use of these two constituents. For example, fuel oil may be cracked by vapors of gas oil or gas oil may be cracked by the vapors of the kerosene. When gas oil is vaporized to crack fuel oil the pressures which are used in the pipe still and the cracking still are not so high as when kerosene is vaporized for cracking either gas oil or fuel oil. Further, when kerosene vapors are used for cracking gas oil, the temperatures and pressures maintained in the pipe still and the cracking still are higher than when kerosene vapors are used for cracking fuel oil.

The details of construction of the pipe still and furnace are not specifically claimed in this application. The furnace 46 comprises a combustion chamber 134 in which oil or gas are ignited and burned and the gases from the chamber 134 pass around a baffle 136 into a heating chamber 138. The upper end of the chamber 138 receives the highest temperature gases so that the upper coils of the pipe still 44 are subjected to the highest temperatures. As the gases pass between the pipe coils they are gradually cooled so that the lower coils of the pipe still are subjected to the lowest temperature. The combustion gases leave 75

ing the chamber 138 pass through a flue 140 to a chimney 142.

The drawing only diagrammatically illustrates the apparatus and it is to be understood that the 5 cracking still 20, the dephlegmating section 30 and the separating section of the tower 32, and the pipes 40 and 48 may be well insulated to preserve the heat in the oil circulating through this apparatus. Also, insulation may be provided for 10 the residuum still 106 and pipes 108 and 122. Further, the pump 42 would be one of the approved forms of hot oil pumps.

The preferred form of the invention having been thus described, what is claimed as new is:

- 15 1. A process of cracking high boiling hydrocarbon oils to form low boiling hydrocarbon oils comprising maintaining a first body of oil of high boiling point, maintaining a second body of oil of lower boiling point, circulating oil from said 20 second body through a heater and returning it to said second body, separating vapors from the heated oil and passing them through the first body of oil.
- 25 2. A process of cracking high boiling point hydrocarbon oils which comprises maintaining a body of high boiling point oil under superatmospheric pressure and at cracking temperature in an externally unheated enlarged cracking zone, vaporizing a portion of a body of lower boiling 30 point oil, separating the vapors formed, superheating the separated vapors and cracking the higher boiling point oil in said body by passing therethrough in intimate contact said superheated vapors.
- 35 3. A process of cracking high boiling point hydrocarbon oils to form low boiling point hydrocarbon oils, comprising maintaining a first body of high boiling point oil, maintaining a second body of oil of lower boiling point, circulating oil from 40 the second body through a heater and returning it to the said second body, separating vapors from the heated oil, superheating the vapors and passing them through the first body of oil.
- 45 4. A process of cracking high boiling point hydrocarbon oils to form low boiling point hydrocarbon oils comprising maintaining a body of oil of high boiling point, maintaining a second body of oil of lower boiling point, circulating oil from 50 said second body through a heater and returning it to the said second body, separating vapors from the heated oil, injecting steam into the vapors and passing them through a superheater and passing the mixture of steam and superheated oil 55 vapors through the body of high boiling point oil.
- 60 5. A process of cracking high boiling hydrocarbon oils to form low boiling hydrocarbon oils comprising maintaining a first body of high boiling point oil, maintaining a second body of lower boiling point oil, circulating oil from said second body through a heater and returning it to the said second body, separating vapors from the heated oil, and passing them through the first body, and scrubbing vapors leaving the first body 65 with the lower boiling point oil.
- 65 6. A process of cracking high boiling point hydrocarbons to form low boiling point hydrocarbons comprising maintaining a first body of oil of high boiling point, maintaining a second body of oil of lower boiling point, circulating oil from 70 said second body through a heater and returning it to the said second body, separating vapors from the heated oil and passing them through the first body, and scrubbing vapors 75 furnished in the first body with fresh incoming high

boiling point oil to hold back the major portion of the condensates having a boiling point higher than that of the lower boiling point oil.

7. A process of cracking high boiling point hydrocarbons to form low boiling point hydrocarbons comprising maintaining a first body of oil of high boiling point, maintaining a second body of oil of lower boiling point, circulating oil from 10 said second body through a heater and returning it to the said second body, separating vapors from the heated oil and passing them through the first body, scrubbing vapors formed in the first body with fresh incoming high boiling point oil to hold back condensates having a boiling point higher than the low boiling point oil, and further 15 scrubbing the remaining vapors with fresh incoming lower boiling point oil to condense a further portion of said vapors.

8. A process of cracking high boiling point hydrocarbons to form low boiling point hydrocarbons comprising maintaining a first body of oil of high boiling point, maintaining a second body of oil of lower boiling point, circulating oil from 20 said second body through a heater and returning it to the said second body, separating vapors from 25 the heated oil and passing them through the first body, and periodically transferring to the first body high boiling point oil accumulating in the second body.

9. A process of cracking high boiling point hydrocarbons to form low boiling point hydrocarbons comprising maintaining a first body of high boiling point oil, maintaining a second body of lower boiling point oil, circulating oil from 30 said second body through a heater and returning it to the said second body, separating vapors from the heated oil, and passing them through the first body of oil, condensing vapors leaving the first body and withdrawing heavy residuum from 35 the first body.

10. A process of cracking high boiling point hydrocarbons to form low boiling point hydrocarbons comprising maintaining a first body of high boiling point oil, maintaining a second body of lower boiling point oil, circulating oil from 40 said second body through a heater, and returning it to the said second body, separating vapors from the heated oil and passing them through the first body, and intermittently withdrawing heavy residual oil from both bodies.

11. A process of cracking high boiling point hydrocarbons to form low boiling point hydrocarbons comprising maintaining a first body of high boiling point oil, maintaining a second body of lower boiling point oil, circulating oil from 50 said second body through a heater and returning it to the said second body, separating vapors from the heated oil and passing them through the first body, withdrawing the heavy residuum from 55 the first body, distilling the residuum, and returning condensate obtained therefrom to the first body.

12. A process of cracking high boiling point hydrocarbons to form low boiling point hydrocarbons comprising maintaining a first body of high boiling point oil under pressure, maintaining a second body of lower boiling point oil under pressure, circulating oil from 60 said second body through a heater and returning it to the said second body, separating vapors from the heated oil and passing them through the first body, withdrawing heavy residuum accumulating 65 in the said oil bodies, reducing the pressure of the residuum and distilling the same by virtue of 70 75 75

- its superheat and returning the resulting condensate to the first body.
13. A process of cracking high boiling point hydrocarbons to form low boiling point hydrocarbons comprising maintaining a first body of high boiling point oil under sufficiently high pressure for cracking, maintaining a second body of lower boiling point oil, vaporizing oil of the second body under pressure, and passing the vapors through said first body, continuously supplying the high boiling point oil to said first body and the lower boiling point oil to be vaporized, and periodically transferring oil from the second body to the first body.
14. A process of cracking high boiling point hydrocarbons to form low boiling point hydrocarbons which comprises maintaining a first body of high boiling point oil under pressure, maintaining a second body of lower boiling point oil under pressure, continuously supplying high and low boiling point oils to their respective bodies, vaporizing oil of the second body and forcing the vapors through the first body, condensing vapors leaving the first body, and preheating the oil supplied to both said bodies by vapors leaving the first body.
15. A process of cracking high boiling point hydrocarbons to form low boiling point hydrocarbons comprising maintaining a first body of high boiling point oil under pressure, maintaining a second body of lower boiling point oil under pressure, continuously supplying high and low boiling point oils to their respective bodies, vaporizing oil of the second body and forcing the vapors through the first body, scrubbing vapors leaving the first body with oil advancing to both of the said bodies, and preheating the high boiling point oil advancing to the first body by a heat interchange with vapors from the first body.
16. A process of cracking heavy hydrocarbons to form low boiling point hydrocarbons therefrom comprising maintaining a first body of high boiling point distillate under pressure, maintaining a second body of lower boiling point distillate under pressure, vaporizing oil of the second body at a temperature sufficiently high to crack oil of the first body and passing the vapors through the first body, fractionally condensing vapors leaving the first body under pressure, returning a higher boiling point fraction to the first body, and passing a lower boiling point fraction to be vaporized with oil of the second body.
17. An oil distilling apparatus comprising a cracking still, a separator, means for introducing oil into said still, a heater, means for circulating oil in a closed circuit from the separator through the heater and return, means for introducing oil into the closed circuit, means for conducting vapors from the separator to the cracking still, a dephlegmator connected to the still, means for conducting condensate from the dephlegmator directly to the heater, and a condenser connected with the dephlegmator.
18. An oil distilling apparatus comprising a cracking still, a separator, means for introducing oil into the still, a heater, means for circulating oil in a closed circuit from the separator through the heater and return, means for introducing oil into the closed circuit, a vapor connection between the upper portion of the separator and the lower portion of the still, a vapor sealing leg in said separator extending vertically below the point of vapor connection with the still, and a condenser connected with the still.
19. An oil distilling apparatus comprising a

cracking still, a separator, means for introducing oil into the still, a heater, means for circulating oil in a closed circuit from the separator to the heater and return, means for introducing oil into the closed circuit, means for conducting vapors from the separator to the cracking still, a liquid scrubbing condenser in the upper portion of the still, a dephlegmator having a vapor connection with the still, means for conducting condensate from the dephlegmator to the separator, and a fractional condenser connected with the dephlegmator.

20. An oil distilling apparatus comprising a cracking still, a separator, means for introducing oil into the still, a heater, means for circulating oil in a closed circuit from the separator through the heater and return, means for introducing oil into the closed circuit, means for conducting vapors from the separator to the cracking still, a dephlegmator and a series of surface condensers connected in succession with the still, and means for returning condensates from the dephlegmator and condensers to the separator.

21. An oil distilling apparatus comprising a cracking still, a separator, means for introducing oil into the still, a heater, means for circulating oil in a closed circuit between the separator and the heater, means for introducing oil into the closed circuit, a vapor line for conducting vapors from the separator to the lower portion of the still, a pipe connection between the upper portion of the still and the separator, valves in the vapor line and pipe connections by which oil may be transferred from the separator to the still.

22. An oil distilling apparatus comprising a cracking still, a separator, a heater, means for circulating oil in a closed circuit between the separator and the heater, means for introducing vapors from the separator into the still, means for introducing oil into the still, means for scrubbing vapors formed in the still with the incoming oil, a dephlegmator connected with the still, means for introducing oil into the dephlegmator, means for scrubbing vapors passing through the dephlegmator with oil introduced therein, means for conducting oil and condensate from the dephlegmator into said closed oil circuit, and a condenser connected with the dephlegmator.

23. In the process of cracking petroleum oils, in which a reflux condensate is produced from cracked vapors and a distillate is produced from cracking still residuum, the improvement which comprises introducing said distillate into a cracking chamber where a body of oil is maintained at a cracking temperature, vaporizing said condensate, heating the vapors to a temperature substantially higher than the oil of said body in a separate zone, and introducing the resulting vapors while at a high temperature into said chamber to heat and crack said distillate.

24. In the process of cracking petroleum oils, in which a reflux condensate is produced from cracked vapors and a distillate is produced from cracking still residuum, the improvement which comprises introducing said distillate into a cracking chamber where a body of oil is maintained at a cracking temperature, independently vaporizing and superheating said condensate, and using the resulting highly heated vapors as the sole heating means, to heat and crack said distillate.

25. In the process of cracking petroleum oils, in which a reflux condensate is produced from cracked vapors and a distillate is produced from cracking still residuum, the improvement which

- comprises heating said distillate and introducing it into a cracking chamber where a body of oil is maintained at a cracking temperature, independently heating said condensate to a temperature substantially above that maintained in said chamber, mingling the vapors produced from said operations, and fractionally condensing the combined vapors from said heating and cracking operations to produce said condensate.
- 10 26. The process of cracking hydrocarbon oils, which comprises heating reflux condensate to a high temperature under pressure and passing the resulting products into an enlarged chamber where a body of oil is maintained, withdrawing 15 and distilling residuum from said chamber, separately heating the resulting residuum distillate and introducing it into a separate cracking chamber where a body of oil is heated and maintained at a cracking temperature, and passing vapors 20 from said chambers into a reflux condensing zone to produce said reflux condensate.
27. The process of cracking petroleum oils, which comprises maintaining a body of oil in a chamber at a high temperature under superatmospheric pressure, passing oil from said chamber through a heater and returning the heated products to said chamber, passing residuum from said chamber into a vaporizer maintained under a lower pressure than said chamber, thereby to 25 vaporize portions of said residuum by the heat contained therein, removing vapors from said vaporizer, producing a condensate therefrom, introducing the condensate into a separate cracking zone where it is subjected to cracking conditions 30 of temperature and pressure, removing vapors from said cracking zone to a vapor fractionating zone in which a reflux condensate is produced, and introducing at least a portion of said reflux condensate into said heater.
- 35 40 28. An oil heating apparatus comprising a furnace having a fire chamber and a tube chamber separated from the fire chamber by a bridge wall over which heating gases from the fire chamber enter the tube chamber at the top and having an outlet for heating gases at the bottom of the tube chamber, a bank of horizontally disposed tubes in said tube chamber, an external tank, a circulating pump and connections between said tubes, pump, and tank, whereby the pump forces 45 oil from the tank successively through tubes at successively higher levels in said tube bank and thence back into the chamber.
- 50 55 29. An oil treating apparatus, comprising a pipe still in which the oil to be treated is subjected to heat while in liquid phase, a separating
- chamber into which the oil from said pipe still is discharged for separation of vapors from unvaporized oil constituents, a superheater in which the vapors from said separator are subjected to a high temperature while in vapor phase, means 5 for heating the vapors in the superheater to a high temperature with products of combustion, and means for utilizing the same products of combustion which are used for heating the vapors in the superheater at a high temperature for 10 heating the oil in the pipe still at a lower temperature.
30. An oil distilling apparatus comprising a plurality of enlarged chambers adapted to contain bodies of oil, a pipe still heater, means for 15 conducting oil from one of said chambers through said heater wherein the oil is heated to a high temperature and then back to said chamber, separate means for conducting vapors and liquid from said chamber into the body of oil maintained in 20 a second chamber in which said vapors are used for heating the oil therein, and means for introducing fresh oil charging stock into said second chamber.
31. A process of cracking petroleum oils, which 25 comprises maintaining a plurality of bodies of oil under a superatmospheric pressure and at a high temperature, passing oil at a superatmospheric pressure from one of said bodies through a heating zone wherein the oil is heated to a high temperature, separating vapors produced in said heating zone from unvaporized oil constituents, passing unvaporized oil constituents from said heating zone directly into the body of oil from 30 which they were withdrawn, contacting the vapors 35 from said heating zone with the oil in a separate body of said plurality of bodies to heat and crack portions thereof, producing a reflux condensate from the combined vapors produced in the heating and cracking operations, and introducing at 40 least a portion of said reflux condensate into said heating zone.
32. An oil distilling apparatus comprising a cracking still adapted to contain a body of oil, a separator, means for introducing oil into the still, a heater, means for circulating oil in a closed path from the separator through the heater and back to the separator, means for introducing oil 45 into said closed path, means for superheating vapors from said separator and for introducing the resulting superheated vapors into the body of oil in said still, a condenser connected with the still, and means for withdrawing residuum from 50 the still.
